UNITED STATES PATENT OFFICE.

JAMES MONTGOMERY, OF EAST MILLSTONE, NEW JERSEY.

STOCK-CAR.

SPECIFICATION forming part of Letters Patent No. 397,199, dated February 5, 1889.

Application filed April 4, 1888. Serial No. 269,597. (No model.)

To all whom it may concern:

Be it known that I, JAMES MONTGOMERY, a citizen of the United States, residing at East Millstone, in the county of Somerset and State 5 of New Jersey, have invented a certain new and useful Improvement in Stock-Cars, of which the following is a full, clear, and exact description.

This invention relates to improvements in 10 cars the bodies of which are specially designed and built for feeding and watering live stock in the cars while in transit, although parts of the improvements are applicable to the common stock-cars now in use in 15 the railways of the United States, as may be seen by reference to my concurrent application for patent entitled "Improvement in stock-cars, Case B," and as will appear more fully hereinafter.

20 The invention consists in the watering appliances, also in the hay-racks, and also in details of construction and arrangement of parts, as I will now proceed more particularly to set forth and claim.

25 In the accompanying drawings, in the several figures of which like parts are similarly designated, Figure 1 is a side elevation of one form of my stock-car. Fig. 2 is a vertical cross-section taken in the plane of line $x-x$, 30 Fig. 1. Fig. 3 is a perspective view of one form of hinged or folding shutter-board for the hay-rack, showing the shutter-board in unnatural position. Figs. 4 and 5 are side and perspective views of two forms of water- 35 distributors. Fig. 6 is a section similar to Fig. 2, but showing the form of hay-rack illustrated in Fig. 3. Fig. 7 is a perspective view of details of one form of watering apparatus, the same as is shown in Fig. 1; Figs. 8, 9, and 40 10, respectively, sectional, perspective, and plan views giving in detail the construction of the preferred form of drinking-trough. Figs. 11 to 14 are diagrams illustrating details of drinking-troughs; and Fig. 15 is a sectional 45 end view of the drinking-trough shown in Figs. 1 and 7, and in addition showing a gutter for waste water.

The body a of the car is made with doors b at opposite ends of opposite sides (see full 50 and dotted lines, Fig. 1) for the greater convenience in loading and unloading and for the better arrangement or distribution of the

feeding and watering appliances, presently described.

In one or both ends c of the car a small 55 door, d , is provided (see Fig. 2) for facilitating the entrance of a person into the car when for any purpose it is necessary for him to get at and among the animals or other freight. Trap-doors e are also provided in 60 the end or ends of the car, and substantially on the floor-level, (see Fig. 6,) for facilitating the loading and unloading of rails, lumber, and other long freight.

65 Hay-bins ff are arranged on each side of the car in the roof, and open into hay-racks, as will presently appear. The hay-bins terminate short of the center of the car, so as to leave an open space for the clearance of snow and rain and for the reception of the water 70 tank or receiver g , as set forth in my concurrent application before referred to; but in order to complete this specification I will say here that this tank or receiver is a metal vessel having its bottom g' slanting both ways 75 from a median line or plane, so as to thoroughly empty or drain the vessel, and constructed with two inlet-columns, $g^2 g^2$, which straddle the ridge-pole h of the car and project through the roof of the car on each side 80 of the ridge-pole, thus obviating the necessity of cutting away the ridge-pole for the reception of the water-tank, as has been the case in some prior constructions. The tank is rigidly suspended from the roof of the car in 85 this position and location by any suitable means. A hinged cover, g^3 , is attached to the mouths of the inlet-columns $g^2 g^2$ to exclude dirt and cinders, and also to cover or replace the break in the usual foot or running board on the top of the car, and to facilitate the filling of the tank—for example, by means of the apparatus forming the subject of my concurrent application entitled, "apparatus for supplying trains of stock- 90 cars with water." The inlet-columns $g^2 g^2$ have the overflow-pipes $g^4 g^4$ leading down to the eaves of the car-roof, and the distributing-pipes $g^5 g^5$ leading from opposite sides of the bottom of the tank into position to supply 95 the drinking-troughs with water.

100 In Figs. 1, 7, and 8 I have shown the drinking-troughs i as composed of a number of individual basins, (heretofore patented, and

hence not, *per se*, of this invention,) which are suitably journaled in the car. The basins are arranged, by preference, along each side of the car from the doors to the opposite ends, 5 and all the basins on each side, in order to be simultaneously operable, are connected together by rods j , extending from the door at each side of the car to the opposite end. The journals of the troughs are projected through 10 the ends of the car, and are squared and provided with crank-arms j' , which are connected to rods j^2 , secured to the ends of the car and extended up into convenient reach of a train-hand on the roof of the car. By this construction all of the basins on each side of the car may be operated simultaneously to bring them into position to contain water for the animals in the car to drink, and afterward to tilt or tip them toward the sides of the car to 15 empty them and throw the water outside the car.

In my Case B, I have confined the invention of trough-operating mechanism to means for operating simultaneously the troughs on opposite sides of the car, at the same time I have 20 provided for operating them singly; but I reserve to this case the operating of the troughs singly by the direct connection of the operating-rod to a crank or arm applied separately to the journals of each trough. However, I may use in this case the trough-operating mechanism of the other, though I do not claim here specifically such mechanism.

For the purpose of catching the splash from 25 the drinking-troughs, and also to insure the discharge of the waste water outside the car, I employ gutters k beneath the troughs, (see specially Figs. 2, 6, and 15 for details,) and referring specially to this last-named figure 30 (15,) the gutters are constructed as follows: A board, k' , set on edge is extended along the front edge of the trough throughout its length, and a bottom board, k^2 , is connected by a water-tight joint with this board k' , and 35 has a fall or pitch downward and outward from the said board, being extended slightly beyond the outside face of the car, so as to insure the conveyance of the waste water not only outside the car but also away from it. 40 The boards composing the gutter are firmly supported and braced and the gutter secured to the side of the car by metallic brackets k^3 .

The boards k' , herein referred to as "protection-boards," subserve the ends of preventing 45 injury to and dislocation of the troughs by the surging and crowding of the cattle, and also by the loading of bulk freight, such as boxes, lumber, rails, &c.

As heretofore constructed, the drinking-troughs have been of sufficient width to fill 50 the space between the side walls of the car and these protection-boards when the troughs are in position for holding water, as in Fig. 11; but the depth of the troughs is so much 55 less than their width, or their journals are so disposed that when the troughs are not in use and are turned up against the sides of the car

there is quite a space left between the boards and troughs, as indicated in Fig. 12. Now it is not an uncommon thing for rearing animals 60 to get their legs over these protection-boards and between them and the reversed troughs, and oftentimes in their efforts to free themselves their legs are broken. To remedy this evil, I make my troughs of equal width and 65 depth on radii from their journals extending to their sides and bottom, and, if desired, to their top, so as to fill in the space between the side of the car and the protection-board in both positions of the troughs, as clearly indicated in Figs. 13 and 14, disposing of their journals appropriately to this end.

Where the trough is composed of a number of basins they are supplied with water from the tanks at a minimum use of pipe by 70 employing a single conduit, l , over each row of basins, (see Figs. 1 and 7,) with which the distributing-pipes g^2 of the tank are connected. Inasmuch as it is desirable to use as light (and consequently cheap) pipe as possible, I make up the conduit of basin lengths of pipe and unite these lengths of pipe by T 's, 75 into the shanks of which latter nipples or nozzles l^2 are inserted. I prefer this construction because of its economy, for a conduit-pipe of sufficient thickness to admit of tapping in order to insert the nipples would not only add to the weight of the car, but would be expensive. However, I do not exclude from my invention this last form of 80 pipe, but am mindful of the fact that its use would greatly reduce the labor of fitting the T 's. The nipples are curved, preferably, so as to break the force of the downflowing column of water, and hence convey it to the 85 troughs with as little splash as possible. Another and preferred form of trough is shown 90 in detail in Figs. 4, 5, 8, 9, and 10, and it consists of malleable cast heads m , of semicircular shape, or nearly so, provided with right-angled flanges, to which is riveted the body portion m^2 of the trough. The body portion 95 may be sheet iron or steel or other suitable material.

In order to stiffen and brace the trough, I 100 provide flanged partitions m^3 , disposed at suitable intervals transversely of the trough, and riveted, soldered, brazed, or otherwise secured to it. The partitions are provided with 105 openings m^4 at their bottoms, (see Figs. 8 and 9,) so as to permit the passage of the water from one end of the trough to the other. Another function of these partitions is to reduce 110 swash in the troughs. The trough thus constructed may be in a single length extending 115 from one end of the car to the door at the other end, as shown in Fig. 10; or it may be divided and coupled by interlocking heads of 120 any suitable sort, as indicated at m^6 in Figs. 4, 5, and 9.

The troughs may have the intermediate 125 journals, as shown, or they may be hinged to the car-sides at their rear edge. When the troughs are joined, as at m^6 , these joints may 130

be utilized to provide an auxiliary bearing for the troughs.

I do not enter into the details of the bearings or supports for the troughs, as they are 5 within the mechanic's sphere and will be such as circumstances require.

To supply the troughs with water, the distributing-pipes g^6 , coming down from the tank at the center of the car, may be closed by 10 screw-caps n , just above which and in opposition are orifices $n' n'$ in the pipe to eject the water in opposite directions in a gentle manner. This ejection of the water gently and with as little force and splash as possible may 15 be still better secured by the use of the T . (Shown in Fig. 5 at n^2 as applied to the pipe g^5 .) Any device which will divert the falling water from a line following that of the pipe g^5 will accomplish, essentially, the object I have 20 in view. Two forms of hay-rack are shown—one in Fig. 2 and the other in Figs. 3 and 6.

In Fig. 2 the rack o may be of ordinary slatted form, or the peculiar slatted form set forth in Case B. It is hinged at o' to the side 25 of the car, and has a lip, o^2 , supported on a stationary timber or stop, o^3 , near the roof of the car. When in the position of use, Fig. 2, the rack is firmly secured by its hinges and the lip o^2 and stop o^3 . When not desired for 30 use, it may be turned on its hinges o' flat against the side of the car, and be held in that position, as by a hook, o^4 , engaging an eye, o^5 , though any other device may be employed.

35 To close the rack against the animals in the car, shutter-boards p may be hinged at their upper ends to the stops o^3 , or elsewhere, and any suitable medium operable from outside the car may be employed for raising and lowering them.

40 It is taken for granted as understood that the racks may be arranged on either or both of the sides of the car, and that they are accessible from and fed by the hay-bins f .

45 Instead of the hinged flap shutter-board, I may employ a sliding shutter-board constructed and arranged to operate very much like the dampers in doors to stove ash-pits. (See Figs. 3 and 6.) The part o may be as before, 50 and the sliding member may be a duplicate of and secured parallel to the member o , as by clips p' , and it is adapted to be reciprocated longitudinally of the part o . This movement of the sliding shutter-board may be accomplished by a lever, q , pivoted outside the car, so as to be operable from the roof, as shown 55 in Figs. 1 and 3, and connected by a flexible joint, q' , Fig. 3, with the sliding board p . This flexible connection admits of the movement of the hinged portion on its hinges.

60 The stopping and starting of the trains and their passage over rough roads throw the cattle with considerable violence against the ends and sides of the cars, often bruising and otherwise injuring them. I propose to alleviate 65 this difficulty by padding the protection-boards, as indicated at r in Fig. 14, and the

ends of the car, as indicated at $s s s$ in Fig. 2, with such material as cocoa-matting or other durable but yielding fabric.

70 Either form of drinking-trough herein described, and either form of hay-rack set forth in this specification, may be employed in the conversion of ordinary stock-cars into so-called "palace" stock-cars, agreeably with the invention described in my Case B, before mentioned. So, also, the water-distributors may be adapted to that invention.

75 Instead of using the shutter-board hay-racks, I may here employ the rack specified in Case B.

In a word, the parts described in the two cases are interchangeable by obvious mechanical expedients; but I have separated the inventions on the line of adaptability to new 85 cars and to the conversion of old cars, bearing in mind the economical question presented in the two instances, and thus bringing the inventions within the requirements of railway management.

90 What I claim is—

1. In a stock-car, the water-tank g , straddling the ridge-pole substantially midway between the ends of the car and provided with distributing-pipes g^5 g^6 , terminating in outlets composed of horizontal openings leading from opposite sides of such pipes over the drinking-troughs, combined with such troughs, substantially as described.

100 2. In a stock-car, water-tanks g , straddling the ridge-pole substantially midway between the ends of the car and provided with distributing-pipes g^5 g^6 , each having the opposite openings, $n' n'$, and closed by screw-caps n , and arranged over the drinking-troughs, combined with such drinking-troughs, substantially as described.

110 3. The gutter composed of the vertical protection-board k' , slanting bottom k^2 , and braces k^3 , connecting the protection-board and bottom and securing them to the side of the car, in combination with the tilting drinking-trough arranged wholly within such gutter and of a width and depth relatively to its journal to fill the spaces between the protection-board and sides of the car both when in use and when not in use, and means for tilting the troughs, substantially as described.

115 4. The gutter composed of the vertical protection-board k' , slanting bottom k^2 , and braces k^3 , connecting the protection-board and bottom and securing them to the side of the car, in combination with the tilting drinking-trough arranged wholly within such gutter and of a width and depth relatively to its journal to fill the spaces between the protection-board and sides of the car both when in use and when not in use, and having its journal extended through and outside of the end of the car and connected with the crank j' , 120 from which the operating-rod j^2 extends up to the roof, substantially as described.

125 5. A folding hay-rack fixedly hinged at its lower end to the side of the car and adapted

to be folded up flat against the side of the car, and provided with a lip to engage stationary stops depending from the upper part of the car when the rack is inclined for use, substantially as described.

5 6. The hay-rack hinged at its lower end to the side of the car and adapted to fold up against the side of the car, and having a lip to engage stationary stops depending from 10 the top of the car, combined with a shutter-board and means to move it to open and close such rack, substantially as described.

7. A hay-rack for stock-cars having a main slatted portion behind which the hay is placed, combined with a shutter-board hinged to the 15 upper portion of the car and adapted to close and open the rack by a pivotal movement, substantially as described.

In testimony whereof I have hereunto set my hand this 30th day of March, A. D. 1888.

JAMES MONTGOMERY. [L. S.]
